JOHN M. RICE, OF NEW YORK, N. Y., ASSIGNOR TO ROBERT HOE, THEODORE H. MEAD, AND CHARLES W. CARPENTER, OF SAME PLACE.

BRAKE AND ADJUSTING DEVICE FOR WEB-ROLLS OF PRINTING-PRESSES.

SPECIFICATION forming part of Letters Patent No. 628,148, dated July 4, 1899.

Application filed January 11, 1898. Serial No. 666,341. (No model.)

To all whom it may concern:

Be it known that I, JOHN M. RICE, a citizen of the United States, residing at New York, county of New York, and State of New York, have invented certain new and useful Improvements in Friction and Adjusting Devices for the Sheet-Feeding Rolls of Printing-Presses, fully described and represented in the following specification and the accompanying drawings, forming a part of the same.

This invention relates to certain improvements in friction devices and adjusting mechanism for rolls, and is particularly intended and adapted for use in connection with the rolls which supply the paper web to rotary printing-machines.

It is desirable in rotary printing-machines and other analogous machines to which material is fed from a roll in web form to provide the web-roll with a tension mechanism which shall operate to control the feed of the material to the machine. In such devices as heretofore constructed it has been usual to employ a brake pulley or drum mounted on the roll-shaft and to use in connection therewith arms or levers carrying brake-shoes, which arms or levers are pivoted on a common center. Devices were employed to bring together or separate the ends of the levers, so as to increase or decrease the tension on the web. Devices of this character have been objectionable, however, because uneven wear on either the pulley or the brake-shoes, or both, threw the entire device out of adjustment, and consequently seriously interfered with its operation. Furthermore, in machines to which a web is fed it is desirable to provide means for shifting the web-roll sideways in order to cause the web to be properly fed into the machine. This is particularly true of printing-machines on account of the necessity for so positioning the web-roll as to cause the imprint made by the type-cylinders to fall properly on the web with respect to the margins on the page. In the devices heretofore used the means for effecting this sideways adjustment have been more or less complex, causing a considerable loss of time in positioning the web-roll whenever a new roll was put into the machine.

The object of this invention is to produce a tension device for use on the web-rolls of printing-machines and in other similar relations employing a drum or pulley and friction pads or blocks in which the adjustments necessary to vary the amount of friction may be quickly and accurately made and the wear and tear produced by the contacting parts may be readily and easily compensated for.

A further object of the invention is to produce a friction mechanism of the character described in which the necessary sidewise adjustment to properly position the roll may be quickly made and the roll accurately positioned, so as to give the web the proper central lead to the machine.

A further object of the invention is to produce a friction mechanism of the character described in which there shall be a certain degree of automatic adjustment, so that slight inequalities in the roll may be compensated for without requiring the constant attention of the attendant.

With these and other objects in view the invention consists in certain parts, improvements, and combinations to be hereinafter described, and specifically pointed out in the claims hereunto appended.

In the accompanying drawings, which constitute a part of this specification, Figure 1 is a side view of a tension mechanism applied to a web-roll of a printing-machine, certain parts being shown in section. Fig. 2 is a sectional view taken on the line 2 2 of Fig. 3, and Fig. 3 is an end view of the device.

In the embodiment of the invention which has been selected for illustration, A indicates the web-roll; B, the shaft on which it is mounted; D, a part of the frame of a printing-machine, and C the journal-bearing carried by the frame in which the shaft is mounted.

On the shaft B is mounted a friction-head consisting of a drum or pulley E. This pulley has a groove in its face, which groove has the form of a reentrant angle, so as to produce a pulley or drum which may be designated as "double-cone-shaped."

Engaging the double-cone-shaped pulley E are friction blocks or pads F, made of any

suitable material, but preferably of wood. These blocks constitute brake-shoes, which are of V-shape, thus forming salient angles corresponding to the reentrant angle in the 5 pulley-face. These blocks or shoes are preferably two in number and are located on opposite sides of the pulley, and they are pivoted to levers G. These levers are in turn pivoted on studs I, which are suitably mounted 10 in the frame of the machine, thus giving the levers independent pivotal points. The studs I are or may be connected by a cross-brace J of the form shown.

One of the levers G is preferably provided 15 with a pivoted bell-crank lever K, the movement of which is limited by a stop M and which has a bent leaf-spring L, secured thereto in the manner clearly shown in Fig. 3 of the drawings. The other lever is provided 20 with a threaded socket G', in which works a screw-threaded rod T', having a hand-wheel T. The end of the rod which is opposite to that engaging the threaded socket G' bears against the spring L, which has been before 25 described as mounted upon the bell-crank lever K, finding its bearing in a small hole or concavity (not shown) in the spring.

It is obvious that by turning the hand-wheel T in the proper direction the levers G 30 will be separated at their outer ends and the brake-shoes F given a movement in a transverse direction with respect to the drum or pulley, so as to provide for any desired amount of friction on the said pulley or to 35 compensate for the wear on either the block or the pulley. Furthermore, owing to the arrangement of the levers and blocks, the blocks will always adjust themselves to any unevenness in wear. In case the operator desires to 40 quickly or momentarily increase the friction of the brake-shoes on the drum he can do so by operating the upwardly-extending arm of the bell-crank K. When the arm is released, the bell-crank will resume its normal position, 45 with its inner arm bearing against the stop M, which is mounted on the lever G. The spring L, against which the screw-threaded rod bears at one end, will operate to compensate for any minor changes in tension, be- 50 cause of irregularities in the shape of the roll or for other reasons, and cause the roll to turn evenly and steadily under the pull imparted to it by the cylinders of the printing or other machine.

55 Various devices may be used for shifting the friction-drum and the roll laterally, so as to properly position the roll with relation to the machine to which the material composing the roll is to be fed. Preferably, however, 60 this adjustment is effected by means of a screw-threaded short shaft O, which is provided with a hand-wheel N and which engages a suitably-threaded aperture in the frame. The short shaft O is provided with 65 two stationary collars P, between which is held a sleeve R, in which the shaft turns and to which is secured a cross-piece S. This

cross-piece S has its ends provided with perforations, which surround the studs I before referred to. Through these perforations pass 70 hubs H, which extend laterally from the levers G. The ends of the hubs extend through and beyond the cross-piece S and are provided with collars or nuts g, so that the cross-piece is held between these nuts g on one side 75 and the levers G on the other. By turning the hand-wheel N the screw-threaded short shaft O may be given an endwise movement in either direction, and it will carry with it in this movement the cross-piece S and the 80 levers G. The levers G, having their angular faces engaging the groove in the pulley or drum E, will in turn move it and the shaft and paper-roll to which it is connected.

It is of course obvious that the face of the 85 pulley may be formed with a salient angle, the friction-block having the reentrant angle, and in general many changes may be made in the construction of this device without departing from the spirit and scope of the invention, and it is to be understood, therefore, 90 that the invention is not to be limited to the precise details of construction herein set forth. Furthermore, while the device is particularly adapted to use in connection with 95 the web-rolls of printing-machines, it is also capable of use in many other relations, and it is to be understood that its use is not limited to such machines.

What I claim is—

1. The combination of a paper-roll shaft, a friction-head thereon, pivoted brake-shoes adapted to engage therewith, the head and shoes being formed with generally corresponding reentrant and salient angles, and means for adjusting the shoes to and fro in the direction of the shaft to secure the marginal adjustment of the web, substantially as described.

2. The combination of a paper-roll shaft, a friction-head thereon, arms carrying pivoted brake-shoes adapted to engage with the friction-head, the head and shoes being formed with generally corresponding reentrant and salient angles, and said arms being pivoted 115 to the frame, means for adjusting the relation to each other of the outer ends of the arms, and means for moving the arms to and fro with respect to the length of the shaft in order to adjust the margins of the web, substantially as described.

3. The combination of a paper-roll shaft, a friction-head thereon, arms pivoted at different points and carrying pivoted brake-shoes adapted to engage the friction-head, the head and shoes being formed with generally corresponding reentrant and salient angles, a cross-piece, connections between the cross-piece and the brake-shoe arms, and means for moving the cross-piece to and fro with reference to the paper-roll shaft for adjusting the margins of the web, substantially as described.

4. The combination of a paper-roll shaft B,

a double-cone-shaped friction-head thereon, pivoted levers G, pivots I therefor upon the frame, brake-shoes F pivoted to the levers G, cross-piece S, and means for adjusting the 5 cross-piece to and fro with respect to the shaft B, substantially as described.

5. The combination with the roll and its shaft, of a friction-head fixed on the shaft, a friction-block engaging the surface of the 10 friction-head, the head and the block being formed with generally corresponding reëntrant and salient angles, and means for adjusting said friction-block both parallel and transversely to the axis of the roll-shaft, sub- 15 stantially as described.

6. The combination with a roll-shaft, of a friction-head thereon, a brake-shoe engaging the head, the head and shoe being formed with generally corresponding reëntrant and 20 salient angles, a lever to which the brake-shoe is pivoted, means for adjusting the position of the lever so as to increase or decrease the pressure of the shoe on the head, and a spring interposed between the lever 25 and the adjusting means, substantially as described.

7. The combination with a roll-shaft, of a friction-head thereon, a pair of brake-shoes engaging the head, the head and shoes being formed with generally corresponding reëntrant and salient angles, a pair of levers to 30 which the brake-shoes are pivoted, an adjusting device for controlling the pressure of the 35

brake-shoes carried by one of the levers, and a spring carried by the other lever against 35 which the adjusting device bears, substantially as described.

8. The combination with a roll-shaft, of a friction-head thereon, a pair of brake-shoes engaging the head, the head and shoes being 40 formed with generally corresponding reëntrant and salient angles, a pair of levers to which the brake-shoes are pivoted, a screw-shaft mounted on one of the levers, a bell-crank mounted on the other lever, and a plate-spring carried by the bell-crank against which one end of the screw-shaft bears, substan- 45 tially as described.

9. The combination with a roll-shaft, of a friction-head, a pair of levers having inde- 50 pendent pivotal points and carrying pivoted friction blocks or shoes engaging the head, said head and shoes being formed with generally corresponding reëntrant and salient angles, means for operating the levers to cause 55 the blocks to bear with greater or less pressure on the head and means for adjusting the blocks or shoes lengthwise of the roll-shaft, substantially as described.

Signed by me, at New York city, this 10th 60 day of January, 1898.

JOHN M. RICE.
